UNITED STATES PATENT OFFICE.

PHILIPPE BERNARD, OF NEW ALBANY, INDIANA, ASSIGNOR TO W. C. DE PAUW, OF SAME PLACE.

MACHINERY FOR POLISHING GLASS, &c.

SPECIFICATION forming part of Letters Patent No. 361,482, dated April 19, 1887.

Application filed August 30, 1886. Serial No. 212,278. (No model.)

To all whom it may concern:

Be it known that I, PHILIPPE BERNARD, a citizen of Belgium, residing in New Albany, in the State of Indiana, have invented a new and useful Improvement in Machinery for Polishing Glass and other Substances, of which the following is a specification.

My invention relates to machines for grinding, smoothing, and polishing glass and other substances, and has for its object certain improvements in that class of machines in which the rough glass, as delivered from the casting, blowing, and annealing departments of the respective works, when once fastened or secured in the usual manner to the table or platform, is successively ground, smoothed, and polished on the side exposed without resetting or removing the glass therefrom until it is entirely finished.

20 In the specifications of Letters Patent No. 348,311, granted August 31, 1886, to my assignee, W. C. De Pauw, upon my application filed May 17, 1886, I have set forth and claimed one way of accomplishing said result—viz., by 25 combining with the "runners," which perform the grinding operation, polishers adapted to be detachably secured to said runners.

I have also indicated in said specifications that it has before been proposed to accomplish 30 the result I have in view by using, in connection with the same platform or table, a series of frames or carriages—the one for grinding or smoothing, the next for polishing, and so on—each carriage being brought in succession 35 over the platform.

My invention involves the use, in connection with a rotating power-driven glass-carrying table, of a polisher frame or carriage, a polisher-runner vertically adjustable capable 40 of axial rotary movement only over the face of the table, and obtaining that movement solely from frictional contact therewith, and pressure-regulating mechanism, whereby the pressure of the polisher upon the face of the table 45 or the glass thereon can be varied at will while the machine or apparatus is in continuous operation.

I know of no glass-polishing apparatus before my invention in which the parts are thus 50 combined and arranged. The movement of

the polisher-runner by frictional contact only is essential. If it be power-driven in any direction, whether as to rotation or as to a traversing motion across the face of the glass, the glass will be broken by unequal expansion 55 and contraction, and the face of the glass will almost inevitably be scratched and very poor results will be obtained. It is also necessary that the pressure should be nicely regulated and that the means for this purpose should be 60 so arranged as to permit the adjustment or regulation to be made while the machine is in continuous operation. The success of the polishing operation depends upon the heating of the glass, which in turn is due to friction, to 65 obtain and maintain which the machine must be kept in motion. At the same time it is quite as essential to the success of the work, and to avoid accident or breakage, that the workman should be able, without stopping the 70 machine, to gradually increase the pressure, which is very light at first, and to bring it to the point which observation and experience tell him is best calculated to obtain the best polishing action.

I also combine with the foregoing instrumentalities a runner-frame for grinding and smoothing, so that either set of instrumentalities for polishing or for grinding and smoothing may be used interchangeably with the 75 same platform or table.

In the accompanying drawings, Figure 1 represents the grinding and smoothing machine in connection with which my improvement is used. Fig. 2 is the same machine 80 with the grinding and smoothing frame or carriage removed and the polishing-frame put in its place. Fig. 3 is a plan of the polisher proper.

The rotative platform or table on which the 85 glass to be operated on is secured is represented at *f*. It is centrally mounted upon a vertical shaft, *d*, supported and adapted to rotate in the foot bearing, *b*, and upper bearing, *c*, of the foundation *a*. The shaft is rotated by 90 a belt actuating the pulley *e* upon it, or it may be actuated in any other convenient way.

Above the platform in Fig. 1 are suspended the runners *g*, each attached to a vertically-adjustable shaft, *h*, having its bearing 95

in a frame or carriage, *k*, which may be provided with wheels *l*, so as to be capable of more ready movement. Each frame *k* may be separate, as shown in full lines, or both of them may be connected by continuous cross-beams *m*, as indicated in dotted lines, so as to constitute in effect a single carriage, which may be wheeled to any position relatively to the platform, or entirely out of the way to make room for the polisher-carriage. With the shaft *h* is combined the pivoted lever *i*, connected at one end to the upper end of the shaft *h* by a joint in the nature of a swiveled or universal-joint connection, *x*, and at the other end to the regulating-bar *j*.

In Fig. 2 I have represented the same rotary platform or table as in Fig. 1 in connection with a polisher carriage or frame, *k'*. This carriage *k'* is in its construction similar to the carriage *k* in Fig. 1, and it may consist of two separate frames or of two frames connected by cross-beams *m'*, so as to constitute in effect a single carriage. Each polisher consists in the present instance of the polisher-projections *o* and a base, *p*, the projections being covered by felt, *q*, or similar substance.

Each polisher is mounted on and attached to a vertically-adjustable shaft, *h'*, mounted in proper bearings in its frame *k'*, said shaft having a connection, *x*, in the nature of a swiveled or universal-joint connection with one end of a pivoted lever, *i'*, so that, while it may be influenced by said lever so far as pressure upon the glass is concerned, it may revolve freely independently of said lever. To the other end of lever *i'* is jointed the regulating-bar *j'*, by means of which the pressure is regulated.

The polisher-shaft, it will be noted, is not power-driven, although it is free to revolve. By tilting the lever *i'* so as to depress that end to which the polisher-shaft is connected, the polisher is forced down upon the glass with positive, determinate, and regulable pressure, which, together with the rotary movement imparted to the polisher by the frictional contact thus brought about between

it and the rotating platform or glass thereon, causes an efficient and thorough polishing operation to take place.

50

I here remark that I may, in order to effect the polishing operation, remove the grinding-runners from their frames after the grinding and smoothing operations have been performed and replace them by the polishers; but I much prefer the use of separate carriages or frames such as I have illustrated in the drawings.

55

In using the apparatus last referred to, the runner frame or carriage *k* is first brought over the rotative platform, upon which the glass has been previously secured.

The glass is then ground and smoothed, after which the carriage *k* is moved out of the way and the carriage *k'* is brought up to fill its place. The latter is adjusted to proper position, the polisher or polishers are brought down upon the glass with determinate pressure, as before explained, and the glass is thus polished.

60

In conclusion I state that I do not claim, broadly, the interchangeable use of polishing, smoothing, and grinding frames with one and the same platform; but

70

What I do claim as new and of my own invention is—

75

The combination of a power-driven rotating glass-carrying table, a polisher frame or carriage, a polisher-runner vertically adjustable, capable of axial rotary movement only over the face of the table and obtaining that movement solely from frictional contact therewith, and pressure-regulating mechanism, whereby the pressure of the polisher upon the face of the table can be varied at will while the machine is in continuous operation, substantially as and for the purposes hereinbefore set forth.

80

In testimony whereof I have hereunto set my hand, this 28th day of August, 1886, in the presence of two subscribing witnesses.

PHILIPPE BERNARD.
